Primary Examiner — Sheryl Lane*Assistant Examiner* — Nicole Shiflet(74) *Attorney, Agent, or Firm* — I. Morley Drucker;
Fulwider Patton LLP(57) **CLAIM**

The ornamental design for a railing connector, as shown and described.

DESCRIPTION

FIG. 1 is a top view of the railing connector, showing my new design;

FIG. 2 is a right side view of the design illustrated in FIG. 1, the left side view being a mirror image thereof;

FIG. 3 is a front view of the design illustrated in FIG. 1;

FIG. 4 is a top and front perspective view of the design illustrated in FIG. 1; and,

FIG. 5 is a rear perspective view of the design illustrated in FIG. 1.

Portions of the article shown in broken lines form no part of the claimed design.
